UNITED STATES PATENT OFFICE

NORMAN H. GAY, OF LOS ANGELES, CALIFORNIA

PRECOOLING SYSTEM

Application filed October 11, 1929. Serial No. 398,939.

This invention relates to improvements in apparatus and methods for the precooling of transportation vehicles, whereby the contents of such vehicles may rapidly be brought to a low temperature prior to the movement of the vehicles from the loading point, so that the heat of the ripening does not cause a great consumption of ice, etc., during the trip itself, whereby the trip need not be interrupted at frequent intervals for re-icing of the vehicles.

The invention has been illustratively set forth with respect to the precooling of refrigerator cars, for which the invention is particularly adapted.

It has already been proposed to provide precooling plants for this purpose, in which stationary fans and hence relatively immovable circulating devices were provided along- 20 side a track, and the refrigerating cars were brought to these devices and positioned with respect thereto. The circulation of air was then established through the car whereby the contents of the car were brought to the desired 25 low temperature in quick order. The present invention differs from such prior proposals by the provision of a small, light and easily movable vehicle having an air moving means thereon and provided with conduits for connection to the ventilating traps on the refrigerating car, whereby the parts of the structure may be easily attended by one or two men, and brought to the location of the car, instead of relying upon a switching locomotive or similar means to bring the car to the 30 position of the devices.

Further features of the invention concern the details of construction, and will be more clearly set forth in the course of the following specification and claims.

The accompanying drawings illustrate one form of practicing the invention. In these:

Figure 1 is a diagrammatic side elevation 45 of the pre-cooling carriage, located in position opposite a refrigerating car, this car being shown in longitudinal section.

Fig. 2 is a top plan view of the same.

Fig. 3 is an end elevation of the same.

Fig. 4 is a detail section of parts of the

carriage and its track on a large scale, taken substantially on line 4—4 of Fig. 1.

In the drawings, the rails 10 of standard railroad gauge receive the trucks 11 of a refrigerating car 12 having the insulating walls 55 and floor 13, with the internal ice compartments 14, these compartments being separated from the rest of the car by the usual partition walls 15. Above each ice compartment are roof or deck apertures 16 in the respective 60 car, these being normally closable by the hatchways 17 as indicated in dotted lines in the figures with respect to the apertures opened during operation with the present apparatus. It is likewise preferred to provide 65 hanging curtains 18 within the car to compel the movement of the circulating air through the cargo, without affording it a quick passage over the top of the cargo.

Alongside the track 10 are provided the 70 rails 20 which are mounted at a level corresponding to the roof or deck of the car (Fig. 3), and have the walkways 21 parallel there- 75 to for employment by an attendant in moving along the right of way. These tracks 20 are preferably mounted on the upper surface 80 of the channel members 22, and these channel members in turn are supported in some suitable manner, being illustrated as fastened to the top towers 23 located from point to point along the tracks.

The carriage comprises a body 30 having a clear passage from end to end thereof to receive the ventilating fan 31 (Fig. 4) which is driven from an electric motor 32 mounted on the spider arms 33. At the ends of this body 30 are provided the flexible telescoping bellows-like connections 34 which are fitted to the ends of the rigid conduit members 35. The other ends of the conduit members 35 each have downwardly directed elbows 36 provided with flanges 37 to support and seal similar flexible telescoping members 38 which are connected to fittings 39 adapted to cover and seal a pair of apertures 16 of the car, except for the circulation which may be established through the car and conduits and through the body 30 of the carriage.

The carriage likewise comprises a mast having the strut members 40 connected by braces 100

41 and a top member 42, to support the pulleys 43 at either end of the mast structure. The carriage also has the outriggers 44 which pivotally and loosely receive the bifurcated inner ends of the booms 45 which are preferably formed of inverted T irons with stops 46 at their outer ends. The looseness of connection between the outriggers 44 and the booms 45 permits these booms to be moved in a vertical plane.

10 Hangers 47 are adapted to travel on the booms 45 by means of rollers incorporated in their structure in the usual way, and are connected in the usual way. The two hangers 47 15 for each boom which are nearest the mast are shown in Fig. 1 as connected directly and rigidly to the respective conduit 35, while the outermost hanger is provided with a swivel connection 48 to an inverted U-shaped member 49 which has its legs or free ends secured to the fittings 39.

20 Windlasses 50 are provided on the machine to wind up, unwind, or retain in any desired position the respective cable 51 which passes 25 over the respective pulley 43 and is connected to the respective boom 45.

25 The carriage body 30 has the downwardly extending support members 60 (Fig. 4) which have suitable bearings for the axles 61, 62. 30 The axles 61 have wheels 63 resting upon the tracks 20 for the support of the carriage for moving from one part to another while the center of gravity remains between the wheels 63. The axles 62 carry the wheels 64 which 35 are received within channels 22, and become engaged with the underface of the upper walls thereof when the center of gravity of the carriage and booms, etc., is shifted to a point outside of either wheel 63. This structure 40 prevents the upsetting of the carriage although the center of gravity may be shifted to a point outside of the rails 20.

45 In operation, the refrigerator cars are filled in the usual way, preferably having received a previous icing. If the cars, for example, are filled with fresh fruit, it is necessary to not only withdraw the normal heat contained in the cargo, but also to limit the ripening and therewith to diminish the heat produced 50 by the ripening. For this purpose, the present precooling is employed. The tracks 20 may be located parallel to the warehouse W from which the loading has been done (Fig. 3), or in any other desired location. In any 55 event, the cars are brought to a standstill opposite the tracks 20, and the attendants then move a carriage until its body 30 is opposite the center doors of the particular cars to be served. The booms 45 are swung out, and 60 the windlasses 50 backed off until the outer ends of the booms and therewith their fittings 39 are engaged over the open apertures 16, thereby establishing a closed endless conduit through the car body, one aperture 16, one 65 conduit 35 and its fittings, the carriage body

30, the other conduit and its fittings, and other aperture 16. Regardless of the temperature of the air in the car and the conduits at the beginning, this air is rapidly cooled by the ice contained in the end compartments 70 of the car, and by reason of the forced circulation, the cargo is rapidly brought to a very low temperature, thus retarding ripening and reducing the ripening heat which might thus be produced prior to the chilling 75 of the car. The fan 31 is then set in motion to accomplish this circulation, and is caused to continue for a time which may be judged by experience, but is readily ascertained by testing the temperature of the circulating air 80 from time to time.

85 At the end of the precooling, the windlasses are again wound to raise the ends of the booms 45, and the hatchways 17 closed down. The refrigerating cars are then moved to the re-icing depots, and in practice it is found that a single re-icing at this stage is usually sufficient for a train journey of many days, since the fruit has been prevented 90 from development of ripening heat.

95 It will be understood that a similar procedure is employed with each refrigerator car, and that these cars may or may not be coupled in train as they stand alongside the carriage tracks 20. One of these carriages is provided 100 for each car, and the telescoping joints 35 permit the movement of the conduits toward or from each other according to the distance between the apertures 16 of the particular car; the conduits 35 moving easily by reason of their hanger supports from the respective boom 45. Further, owing to the very light construction, it is possible to quickly set and adjust the parts, since a single man can readily raise the outer end of the boom 45 and 105 swing the fittings 30 into place or remove it to one side so that the refrigerating car can be immediately coupled in train and withdrawn from the track. This operation is especially facilitated by the location of the 110 tracks 20 of the walkways 21 and substantially the lever of the car deck or roof, so that this single attendant can move the carriage to the proper position, and operate the windlasses to lower the booms while on the 115 walkways 21. It is then a simple matter to step to the car deck and manipulate portions as may be required to bring their conduit mouths over the apertures 16. The electrical connection can now be established, and all 120 without climbing up or down stairways or ladders.

125 It is preferred to provide separable connection 70 from point to point along the line of the rails 20, as for example, by mounting them on a rail 71 for one of the walks 21, when the rails 20 are located adjacent a single line of track 10.

130 It will be understood that the invention is not limited to the specific form illustrated,

but that it may be varied in many ways within the scope of the appended claims.

What I claim as new and desire to secure by Letters Patent is:

- 5 1. In a precooling system for refrigerated vehicles, a track, a carriage movable along said track and supporting a conduit and a fan in said conduit, means whereby refrigerated vehicles may be positioned adjacent said track, said conduit being divided into sections connected for relative movement, and said carriage including a supporting means for the sections of the conduit to permit such relative movement.
- 10 2. In a precooling system for refrigerated cars, a railroad track upon which said cars may be located, an elevated track extending parallel to said railroad track and elevated thereabove and at the substantial height of the car roof, a carriage movable along said latter track, said carriage comprising a conduit comprising relatively movable sections, a mast on said carriage and means held by the mast to support outer sections of said conduit, a fan carried by said carriage and located in said conduit, and connections at the ends of said conduit adapted to fit around and seal from the atmosphere the hatchways of the refrigerated car.
- 15 3. A system as in claim 2, in which the relatively movable sections of said conduit are connected by flexible telescoping bellows, and said end connections comprise rigid members to fit over the hatchways and flexible telescoping bellows connecting said rigid members and the ends of the conduit sections proper.
- 20 4. In a system for precooling refrigerated cars, a railroad track to receive the cars, a track parallel to said railroad track and elevated at substantially the level of the car roofs, a carriage movable on said latter track, a mast mounted on said carriage and having a pulley thereon, a swinging boom adapted for movement in horizontal and vertical planes and pivoted to said carriage, a windlass on said carriage operable by an attendant at the level of the car roof, a cable operated by said windlass and passing over said pulley and connected to said boom to move the same in a vertical plane, a conduit comprising relatively movable sections supported by said carriage and boom, and including a flexible telescoping joint permitting the variation of the distance of the end of said conduit from and its position with respect to the said carriage.
- 25 5. A system as in claim 4, in which the boom comprises a rail, a hanger adapted to travel on said rail and a connection between said hanger and a section of said conduit movable relatively to said carriage.
- 30 6. A system for precooling refrigerated cars comprising a railroad track on which the cars may be located, a second track ele-

vated at a level substantially that of the car roof, a carriage movable on said second track and comprising a rigid conduit section, relatively movable conduit sections having flexible telescoping connections with said fixed conduit section, a mast on said carriage, swinging booms pivoted to said carriage for movement in horizontal and vertical planes, and means connected to said mast and booms for moving said booms in the vertical plane, substantially rigid end members adapted to fit over the car hatchways, and flexible telescoping members connecting said end members to the relatively movable sections of said conduit.

70 7. A system as in claim 6, in which the second tracks are mounted on channel members and said carriage has wheels located in the channels of said channel members and adapted to engage the upper walls thereof to prevent capsizing of the carriage when the booms are swung in a horizontal plane.

In testimony whereof, I affix my signature.

NORMAN H. GAY.
